(57) **CLAIM**

The ornamental design for a bottle, as shown and described.

DESCRIPTION

FIG. 1 is a top perspective view of a first embodiment of a bottle showing our new design;

FIG. 2 is a top view of the first embodiment of the bottle shown in FIG. 1;

FIG. 3 is a front view of the first embodiment of the bottle shown in FIG. 1;

FIG. 4 is a right view of the first embodiment of the bottle shown in FIG. 1;

FIG. 5 is a rear view of the first embodiment of the bottle shown in FIG. 1;

FIG. 6 is a left side view of the first embodiment of the bottle shown in FIG. 1;

FIG. 7 is a bottom view of the first embodiment of the bottle shown in FIG. 1;

FIG. 8 is a top perspective view of a second embodiment of a bottle showing our new design;

FIG. 9 is a top view of the second embodiment of the bottle shown in FIG. 8;

FIG. 10 is a front view of the second embodiment of the bottle shown in FIG. 8;

FIG. 11 is a right view of the second embodiment of the bottle shown in FIG. 8;

FIG. 12 is a left side view of the second embodiment of the bottle shown in FIG. 8;

FIG. 13 is a rear view of the second embodiment of the bottle shown in FIG. 8; and,

FIG. 14 is a bottom view of the second embodiment of the bottle shown in FIG. 8.

The broken lines in the drawings showing the bottle neck and pour spout and lines on the body of the bottle illustrate the portions of the design that form no part of the claim.

1 Claim, 8 Drawing Sheets
